UNITED STATES PATENT OFFICE.

JACOB J. FROESS, OF ERIE, PENNSYLVANIA.

MUSIC-DESK FOR PIANOS.

1,310,472.

Specification of Letters Patent.

Patented July 22, 1919.

Application filed October 31, 1917. Serial No. 199,450.

To all whom it may concern:

Be it known that I, JACOB J. FROESS, citizen of the United States, residing at Erie, in the county of Erie and State of Pennsylvania, have invented certain new and useful Improvements in Music-Desks for Pianos; and I do hereby declare the following to be a full, clear, and exact description of the invention, such as will enable others skilled 10 in the art to which it appertains to make and use the same.

My invention relates to improvements in music desks for pianos and particularly to means for supporting the front panel of a 15 piano having a graphophone and record cabinet mounted in the upper portion of the piano case.

The object of my invention, is to provide a piano of this character with a front panel 20 which can be either adjusted to entirely close the front of the piano and conceal the graphophone and record cabinet, or which can be adjusted outwardly for the purpose of supporting a sheet of music in front of 25 the panel, or which can be adjusted downwardly a sufficient distance to disclose the graphophone and record cabinet, when it is desired to use the graphophone. I obtain these three adjustments by my improved 30 mechanism for supporting the panel.

My invention consists in the novel features hereinafter described in detail, reference being had to the accompanying drawings, in which I have illustrated one form 35 or embodiment of my invention, and the said invention is more particularly pointed out in the appended claims.

Referring to the drawings:

Figure 1 is a front view of a combined 40 graphophone and piano showing the front panel of the piano case in lowered or open position to disclose the graphophone and record cabinet, which is mounted in the upper part of the piano case.

Fig. 2 is a rear view of the panel showing 45 the mechanism upon which the same is mounted in the piano case.

Fig. 3 is a vertical sectional view of a portion of the piano case, showing the panel 50 in closed position and the mechanism which supports the same.

Fig. 4 is a similar view showing the panel 55 swung outwardly into position to support a sheet of music.

Fig. 5 is a view showing the panel in

lowered position to display the graphophone and record cabinet.

In the drawings, 1 represents a piano case having a shelf 2 extending across the upper portion of the interior of the same and supporting a record cabinet 3 and a graphophone 4 having a horn 5.

The sides 6 of the piano are provided with vertical grooves 7 in which are slidably mounted pins 8 which project from the side 65 edges of the panel 9 of the piano case. A rock shaft 10 has its ends journaled in the sides of the piano case and carries two arms 11 which have their free ends pivotally connected at 12 to one end of links 13. The 70 other ends of the links 13 are pivotally connected at 14 to blocks 15, secured to the back of the panel.

Brackets 16 are secured to the sides of the piano case and are provided with slots 17 75 having substantially vertical portions 18 terminating at their upper ends in substantially horizontal portions 19 into which merge notches 20 and 21. Brackets 22 are secured to the rear of the panel near the 80 ends of the same and carry near their rear ends, pins 23 which slidably engage the slots 17.

An angle iron 24 extends across the upper portion of the piano case and coil springs 25 85 have their upper ends secured to this angle iron and their lower ends secured to the back of the panel, as shown at 26.

When the panel is closed the piano case presents the appearance of an ordinary 90 piano and the piano may be played as such, without interference by the graphophone. If it is desired to play the graphophone alone or simultaneously with the piano, the lower end of the panel is pulled forward and 95 then downwardly until it rest in the position shown in Figs. 1 and 5.

When the panel is closed, the panel supporting means rest in the position shown in Figs. 2 and 3, and the coil springs 25 will 100 retain the same in this position. If it is desired to use the panel to support a sheet of music, the lower end of the panel is pulled outwardly and this will cause the pins 23 to travel from the notches 20 to the notches 105 21 and the springs 25 have a tendency to hold the pins in this position.

When it is desired to play the graphophone, the lower end of the panel is pulled outwardly and the panel then moved down- 110

wardly to the position shown in Figs. 1 and 5. This causes the pins 8 to descend in the guides 7 and causes the pins 23 to travel downwardly in the slots 17 until they reach the position shown in Fig. 5. Whenever the panel is moved outwardly or downwardly the rock shaft 10 will be turned and the arms 11 and links 13 will then aid in supporting the panel in the position to which it has been moved.

The springs 25 are not absolutely essential although they aid in lifting the panel and supporting it in its various positions.

What I claim and desire to secure by Letters Patent is:

1. The combination with a piano case having its sides provided with guiding means, of a panel slidably engaging said guiding means, members projecting from the rear of said panel and carrying pins, and brackets provided in said case having slots in which said pins slide.

2. The combination with a piano case having its sides provided with interior grooves, of a panel having laterally projecting pins which pivotally and slidably engage said grooves, a rock shaft mounted in the piano

case and having arms, links connecting said arms and the panel, slotted brackets located in the piano case, brackets secured to the rear of the panel and having pins which engage the slots of the slotted brackets, and springs secured to said panel and to a stationary portion of the piano case.

3. The combination with a piano case having its sides provided with interior grooves, of a panel having laterally projecting pins which pivotally and slidably engage said grooves, a rock shaft extending horizontally across the interior of the piano case and having its ends journaled in the sides of the case, arms rigidly connected to said shaft, links pivotally connected to said arms and to the rear of the panel, brackets secured to the sides of the case and having substantially angular shaped slots, spaced notches merging into said slots, brackets extending from the rear of said panel and having laterally projecting pins movably engaging said slots and adapted to engage said notches for securing the panel in different positions.

In testimony whereof I affix my signature.

JACOB J. FROESS.
